ELECTROMAGNETIC SWITCH

Anthony H. Lamb, Elizabeth, N. J., assignor to
 Weston Electrical Instrument Corporation,
 Newark, N. J., a corporation of New Jersey

Application November 14, 1931, Serial No. 575,067

7 Claims. (Cl. 200—87)

This invention relates to electromagnetic switches or relays and particularly to that type of relay commonly known as an auxiliary or "secondary" relay. Auxiliary relays are designed for the control of circuits in which relatively heavy currents flow, and are actuated by sensitive primary relays located in circuits in which the current flow is not of sufficient magnitude to actuate the auxiliary relay.

An object of the invention is to provide an electromagnetic switch in which the operating force established by a given current flow is approximately constant throughout the major portion of the range of movement of the armature, and increases rapidly during the final movement of the armature. A further object is to provide a switch including an electromagnet having a relatively high ratio of the current value at which the armature will drop away from the pole piece to the minimum current value effective to attract the armature, thereby rendering the switch sensitive to relatively small changes in current flow. More specifically, an object is to provide an electromagnetic switch in which the magnet has a pair of pole pieces between which an armature is mounted for oscillatory movement, one of said pole pieces having angularly disposed faces upon or adjacent which an end and a side face, respectively, of the armature are disposed when the magnet is energized. Further specific objects are to provide relays which include mercury switches mounted directly on the relay armature, the arrangement being such that the mercury switch is tilted, but not lifted, by the armature. These and other objects of the invention will be apparent from the following specification, when taken with the accompanying drawings, in which,

Fig. 1 is a diagrammatic view illustrative of the invention,

Fig. 2 is a somewhat generalized central section through an embodiment of the invention,

Fig. 3 is a side elevation, with parts shown in section, of a relay including tilting contact switches,

Fig. 4 is a plan view of the same, but with the parts in the positions they assume when the relay is energized,

Figs. 5 and 6 are similar side and front elevations, respectively, of a relay carrying another arrangement of tilting switches, the wiring diagram of the circuit being superposed on the Fig. 6 elevation of the relay,

Figs. 7 and 8 are plan and front elevations,

respectively, of a relay having a direct contact switch, and

Fig. 9 is a fragmentary side view of the armature and contact switch with the parts approaching one limit of the armature movement.

In the drawings, the numeral 1 identifies the magnet core which preferably is of U-shape, having an end section and parallel side members which terminate in poles between which the armature 2 is carried on a pivot 3 for rocking movement. When the magnet is energized, the armature is moved to the position shown in Fig. 1, one end of the armature being received within the deep notch or seat formed in one side member by the pole face 4 which extends across the path of movement of the armature end, and the pole face 5 which extends substantially parallel to its path of movement.

The solenoid includes the operating winding 6 and the non-inductive winding 7 which are connected in parallel across the relay terminals 8. One application of the relay is indicated in Fig. 1, in which the sensitive or primary relay 9 includes a contact arm 10 for cooperation with a fixed contact 11 to close the circuit from a current source 12 to the terminals 8 of the relay.

Upon opening of the contacts 10, 11, the discharge of the magnetic field sets up a back electromotive force in the operating winding 6 which tends to produce arcing at the contacts. Due, however, to the provision of the non-inductive winding 7, the energy resulting from the discharge of the electric field is dissipated by the non-inductive winding and arcing at the contacts is suppressed. The protective winding 7 may surround the operating winding 6 and take the form of two equal and oppositely wound sections, the wire preferably being a fine resistance wire which gives the winding 7 a resistance several times that of the operating winding 6.

As shown in Fig. 2, the armature shaft 3 is carried by straps 13 which are secured to opposite sides of the outer ends of the core 1, and a restoring spring 14 is connected between the armature 2 and core 1 to return the armature to normal position when current flow through the solenoid is interrupted or falls below a predetermined value. Due to the shape and arrangement of the pole faces 4 and 5, the effective air gap is comparatively small when the armature is in open position and decreases but slowly as the armature starts moving towards its closed position. Near the limit of its angular movement, however, an increasing proportion of the flux traverses the pole face 4 and the

pull on the armature increases rapidly as the gap between the armature and this pole face closes. The spring 16 is so proportioned that the restoring force which it exerts also increases rapidly during the final angular movement of the armature 2. Due to the relatively uniform traction on the armature during the greater part of its movement, the relay is particularly efficient from the standpoint of the current employed to hold the contacts closed, i. e., the current required to move the armature to closed position is not greatly in excess of that which is required to maintain the armature in closed position. The "pick-up" current may be as low as but fifty per cent in excess of the current required to hold the armature in closed position, thus differing materially from known relays in which the pick-up current is from about three to eleven times the holding current.

20 The rocking movement of armature 2 actuates some form of control device, usually an electrical switch in a circuit in which the current flow may be substantially in excess of the current carrying capacity of the primary relay contacts 25 10, 11.

As shown in Figs. 3 and 4, the laminated core 1, laminated armature 2, and double windings 6, 7 are of the form illustrated in Fig. 2, and this assembly is mounted upon a base 15 of insulating material which is slotted to receive the end section of the core 1. Mounting brackets are arranged at each side of the magnet, flanges 16 of the brackets being secured to the end section of the core 1 while flanges 17 rest upon and 30 are secured to the upper face of the base 15. Terminals 18 for the double solenoid 6, 7 are mounted at one end of the base.

In this particular relay, the switch mechanism is designed to control two auxiliary circuits, and the switches 19 are of the tilting or mercury contact type. The switches are supported by and at opposite sides of the armature 2, being carried in spring clips formed by the ends of the switch brackets 20. The flexible leads 21 of the mercury switches 19 are connected to terminals 22 on the base 15.

It is to be noted that the switches 19 are so positioned by the brackets 20 that the center of gravity of the armature and switch assembly 50 is substantially at the axis of the pivotal shaft 3 of the armature. When, as in the construction illustrated, the armature is supported at its center of gravity, the center of gravity of the switch and switch bracket assembly substantially coincides with the center of gravity 55 of the armature. Since the switches are not lifted by the armature, but are tilted about their center of gravity, the relay will respond to a relatively small amount of energy.

60 It will be apparent that one switch 19 may be eliminated from the relay shown in Figs. 3 and 4 if a control of only one auxiliary circuit is desired and that additional switches may be mounted on armature 2 when more than two 65 circuits are to be controlled by the relay.

In the relay shown in Figs. 5 and 6, the magnet structure and base may be the same as that shown in Figs. 3 and 4, but a tapped solenoid is used to provide an electrical locking 70 relay. One switch 19, its mounting bracket 20 and terminal connections 21, 22 are also identical with that of the described relay; this switch 19 being included in the local circuit that is controlled by the relay. The switch bracket 23 75 terminates in a flange 24 which is curved to

provide seats for two mercury switches 25^a, 25^b, the switches being held in place by a clip 26 that is bolted to flange 24 of the bracket 23. As shown in the wiring diagram that is superposed on the Fig. 6 view, the operating winding 5 comprises two equal sections 6^a, 6^b, which are shunted by non-inductive windings 7^a, 7^b, respectively. The control switch S includes a pair of contacts a, b between which the contact arm c moves. Contact arm c is connected through a current 10 source B to the relay input terminal 18^c that leads to the center point of the windings, and contact a is connected through terminal 18^a to the end of section 6^a of the solenoid. Flexible leads 27^a extend from mercury switch 25^a to 15 the terminal 18^c and to a second terminal 28^a that is connected to the contact arm c of the control switch. Mercury switch 25^b is connected by flexible leads 27^b to the end of the section 6^b of the solenoid, and to a terminal 20 28^b that is connected to contact b of the switch S. With the contact arm c in neutral position, the solenoid is not energized and switches 25^a, 25^b are both open, with switch 19 either open or closed in accordance with the requirements of 25 the particular load circuit. When contact arm c engages contact a, the circuit is closed through winding 6^a, and the armature moves to closed position, closing switches 25^a and 25^b. Switch 25^a is in parallel with contacts a, c, and therefore the armature is retained in closed position when contact arm c moves from contact a. Switch 25^b is in series with the contacts b, c, and therefore the closing of switch 25^b enables 30 the control switch to establish a current flow through the section 6^b of the solenoid when contact c engages the contact b. Upon closing contacts b, c, the direction of current flow 35 through section 6^b neutralizes the existing magnetic field, and armature 2 drops away, and opens switches 25^a, 25^b, thus restoring the original 40 conditions.

As shown in Figs. 7, 8, and 9, the switch is of the direct contact type and comprises a resilient contact arm 29 that is mounted on the armature 45 2, being insulated therefrom by washers 30, and connected by a flexible lead 31 to the terminal 32. A contact 33 is mounted on base 15 for engagement with contact arm 29 when the relay is not energized, and a second contact 34 is positioned for 50 engagement with contact arm 29 when the relay is energized, as shown in Fig. 7.

The contact arm 29 engages the fixed contact 34 before the armature 2 reaches its fully closed position, as shown in Fig. 9, and the final movement of the armature slides the contact arm 29 over contact 34 to provide a self-cleaning contact. The resilient contact arm 29 is flexed during this operation, resulting in a firm engagement 55 of the contacts and also in an increase in the force tending to return the armature 2 to open position, thus offsetting a portion of the increase in magnetic pull which arises as the gap between armature 2 and the pole face 4 closes.

While the invention provides electromagnetic 65 switches that are particularly useful in connection with regulators having delicate contacts, such as the sensitive primary relays previously mentioned, contacting meters, thermometers, contact gauges and the like, it is obvious that the 70 invention may be embodied in more rugged electromagnetic switches actuated by push-buttons or other types of remote control. The switches or relays are therefore useful in many circuit arrangements other than those herein described, 75

and it will be apparent that physical embodiments of the invention may vary materially from those illustrated in the drawings without departing from the spirit of the invention as set forth in the following claims.

5. I claim:

1. An electromagnetic device of the type including a core having opposed poles, an armature of rectangular bar form between said poles, switch mechanism mounted on said armature and forming therewith a moving system, means pivotally supporting said armature for rocking movement about an axis passing substantially through the center of gravity of said moving system, and an operating winding on said core, characterized by the fact that one of said poles includes a face positioned adjacent and substantially parallel to the path of movement of one end of said armature, and a face extending into the path of movement of said armature.
2. In an electromagnetic switch adapted to be controlled by a sensitive relay, a core having spaced poles, an armature, switch mechanism mounted on said armature and forming therewith a moving system, means supporting said armature for rocking movement in the gap between said poles and about an axis passing substantially through the center of gravity of said moving system, and a solenoid for establishing a magnetic field; one of said poles being notched to provide angularly disposed surfaces adjacent the end face and a side face of said armature when the latter attains its solenoid-energized position.
3. The invention as set forth in claim 2, wherein the angularly disposed surface of said notched pole which is adjacent the end face of the armature is substantially coextensive with the said end face.
4. The invention as set forth in claim 2, in combination with spring means opposing movement of said armature by the magnetic flux and

presenting a greater force in opposition to the armature movement during the said final portion of the range of arcuate movement of the armature.

5. In an electromagnet, a core having parallel sides and one end, a solenoid on said core, straps connecting the free ends of said core, a bar-shaped armature between and pivotally supported on said straps, a bracket secured to said armature, and a tilting contact switch mounted on said bracket; the center of gravity of said armature, bracket and switch being substantially on the pivotal axis of said armature.

6. In an electromagnetic switch adapted to be controlled by a sensitive relay, a laminated core having parallel side members joined by an end member, a solenoid on one of said members, a bar-shaped armature pivotally mounted at substantially its center for rocking movement in the gap between the free ends of said members and movable into position substantially normal thereto when said solenoid is energized, the end of one of said side members being notched to provide a seat for receiving one end of said armature when the solenoid is energized, and switch means mounted on said armature with its center of gravity substantially at the pivotal axis of said armature.

7. In an electromagnetic switch, a solenoid, an armature of rectangular bar form and means supporting the same for rocking movement, a U-shaped core having spaced legs extending across the end faces of said armature when the solenoid is energized, one only of said legs being notched to provide a shoulder against which a side face of said armature seats when in closed position, and a tilting contact switch mounted on said armature, the said supporting means comprising a shaft located substantially at the rotational center of said armature and switch.
